United States Patent Office.

ISAAC W. HENDERSON OF LEAVENWORTH, KANSAS.

Letters Patent No. 75,546, dated March 17, 1868.

PEN-HOLDER FOR RULING-MACHINES.

The Schedule referred to in these Letters Patent and making part of the same.

TO ALL WHOM IT MAY CONCERN:

Be it known that I, ISAAC W. HENDERSON, of Leavenworth, in the county of Leavenworth, and State of Kansas, have invented new and useful Improvements in Holders for Pens; and I do hereby declare that the following is a full, clear, and exact description thereof, which will enable those skilled in the art to make and use the same, reference being had to the accompanying drawings, forming part of this specification.

The present invention relates to a holder for pens more particularly intended to be used for the fancy ruling of paper and other sheet material in the manufacture of blank books. This holder is constructed in such a manner that the several pens which it carries can be adjusted to any required distance apart, and the centre pen to rule a line that will be parallel to and equidistant from each of the outside lines, ruled by a double or two single pens, suitably inserted in the pen-holder therefor.

In the accompanying plate of drawings, my improvements in holders for pens are illustrated.

Figure 1 is a side view of the holder, with the ends thereof carrying the pens, in partial longitudinal section; and

Figure 2 a transverse section, taken in the plane of the line $x'x$, fig. 1.

A, in the drawings, represents my improved holder for pens. This holder consists of two arms, B and C, formed and constructed, as well as connected and arranged together, in a manner to be now described.

The arm B, from end to end, is bent or curved, as shown in fig. 1 more particularly, and at one of its ends, D, has inserted in the socket E, suitably made therefor, a double pen, F, or, in other words, a pen with two marking-arms or points, wherein such pen is secured by means of a set-screw, G. The other arm, C, is located above the arm B, and a short distance therefrom; and to its upright piece G it is hung by a hinge, H, that, in construction, is such that the arm C can be slid thereon, either forward or backward, within a certain limit, and at any point, by means of a set-screw, I. This arm C also carries a pen, J, at its outer end, K, which pen, in the present instance, is single, and is secured therein by a set-screw, L, as described for the double pen to the arm B.

The pens F and J extend outward from their respective arms in the same direction with the single pen at its marking-point, between the two marking-points of the double pen, where, by means of a thumb or milled screw, M, it can be adjusted, this thumb-screw screwing through the arm B, and acting against the arm C above, and thereby regulating the distance between the two.

The holder above described has been before stated to be used and more especially designed for the ruling of paper sheets for blank books; but it is plainly manifest that it can be used for other purposes, and is, in use, to be fastened to the machine in proper position by means of a thumb or set-screw, or otherwise.

As the pens are secured on the arms by means of set-screws, it is plainly apparent they can, when broken, be removed, and new ones inserted or substituted for them.

I claim as new, and desire to secure by Letters Patent—

1. A holder for pens, consisting of the two arms B and C, hinged together, substantially as and for the purpose described.

2. The set-screw I, in combination with the above, substantially as and for the purpose specified.

3. The combination of the arms B and C, each adapted to receive a pen or pens, and set-screws G L, substantially as and for the purpose described.

ISAAC W. HENDERSON.
